Patented May 15, 1917.

UNITED STATES PATENT OFFICE.

THOMAS BEAVER, OF SEWELL, NEW JERSEY.

TRAFFIC-SIGNAL.

1,226,445.

Specification of Letters Patent.

Patented May 15, 1917.

Application filed April 15, 1916. Serial No. 91,359.

To all whom it may concern:

Be it known that I, THOMAS BEAVER, a citizen of the United States, residing at Sewell, in the county of Gloucester and 5 State of New Jersey, have invented new and useful Improvements in Traffic-Signals, of which the following is a specification.

The invention is directed particularly to an improvement in traffic signals and 10 particularly to a specific operating means designed for use in connection with a traffic signal described and claimed in an application filed by me on January 12, 1916, Ser. No. 71,768. In said application there is 15 provided immediately in rear of the dash, an operating shaft, which at the outer end, through the medium of gears connected to semaphores or signals, a lever or operating handle being connected to the shaft to simultaneously and similarly actuate the signals 20 at the will of the driver.

In the application described the signals are simultaneously and similarly operated, the present invention being designed particularly for providing a means whereby the signals may be independently as well as simultaneously operated if desired.

The invention in the preferred form of 30 details will be described in the following specification, reference being had particularly to the accompanying drawings, in which:

Figure 1 is a plan illustrating the application of the structure and showing the 35 improved operating means;

Fig. 2 is an enlarged perspective view of the operating means;

Fig. 3 is a vertical sectional view of the same.

40 In connection with the invention described in the application above referred to, there is provided opposing similar signals 1, supported on the vehicle body immediately in rear of the dash, and geared to an operating shaft. In the present instance the said shaft is divided into two shaft sections, 45 2 and 3, arranged in longitudinal alinement and mounted in suitable brackets or guides 4 so that the said sections may be freely 50 rotated. Centrally of the mechanism or adjacent the meeting ends of the shafts 2 and 3 there is provided a bracket 5 having 55 spaced arms 6, through which the respective shaft sections 2 and 3 extend, and in which they are rotatably supported.

An operating lever 7 is provided, includ-

ing a handle portion 8 and a hollow barrel-like body 9. Within the body is supported a socket member 10, preferably of cylindrical form and having diametrically opposed trunnions 11, by which the socket member is supported for pivotal movement at an angle to its axis within the barrel of the operating lever. The socket member is formed with an axial opening 12 of non-circular form in cross section, being shown in the present instance as semi-circular. The respective ends of the shaft sections 2 and 3 are formed at 13 to correspond and fit the axial opening 12 in the socket member, and on each shaft section intermediate the socket member and adjacent arm of the bracket 5, are coiled springs 14. The springs are of sufficient tension to normally maintain the socket member, and thereby 65 70 75 the lever, centrally of the bracket so that both ends of the shaft sections are fitted in the axial opening of the socket member.

The operating lever 7 is provided with a rearward extension 15 formed with an opening to receive the curved guide rod 16 depending from the bracket, the curvature of the rod corresponding to the rotative play of the lever in its operative movement.

A locking arm 17 is pivotally mounted in 85 an opening 18 in the lever and projects in both directions beyond the lever. The rear end of the arm is provided with an offset or tooth 19, to engage a similar recess 20, in an appropriate part of the bracket, while the 90 forward end of the arm 17 underlies the handle portion 8 of the lever and is held spaced therefrom by spring 21.

From the foregoing description it will be apparent that with the operating lever in 95 its central position, said lever may be manipulated, after actuation of the arm 17 to release the lock, to simultaneously rotate both shaft sections 2 and 3 to simultaneously and similarly actuate the signal 1. If, however, it is desired to operate but one signal, 100 the lever is swung bodily in the direction of the shaft connected to that signal, the pivotal movement of the lever being permitted on the connections 15 and 16. This 105 movement causes the socket member to be withdrawn from its connection with the opposing shaft, the pivoting of the socket member compensating for such movement, so that a swinging movement of the lever 110 will operate only the shaft so connected. Upon releasing the pressure upon the lever

the springs 14 return to normal position so that both shaft sections 2 and 3 are again engaged.

What is claimed is:

- 5 1. A traffic signaling apparatus including operating shaft sections, an operating lever, and means carried by the lever to operatively engage either or both of the shaft sections at will.
- 10 2. A traffic signaling apparatus including operating shaft sections, an operating lever, and means carried by the lever to operatively engage either or both of the shaft sections at will, and means for returning the lever to normally engage both shaft sections.
- 15 3. A traffic signal operator including operating shafts, a lever mounted intermediate the shaft sections and adapted for swinging movement, a socket piece pivotally mounted in the lever and having a non-circular axial opening, the ends of the shaft sections being of similar non-circular formation, and adapted to engage the axial opening of the socket piece.
- 20 4. A traffic signal operator including op-

erating shafts, a lever mounted intermediate the shaft sections and adapted for swinging movement, a socket piece pivotally mounted in the lever and having a non-circular axial opening, the ends of the shaft sections being of similar non-circular formation, and adapted to engage the axial opening of the socket piece, and means for pivoting the lever for bodily swinging movement.

5. A traffic signal operator including operating shafts, a lever mounted intermediate the shaft sections and adapted for swinging movement, a socket piece pivotally mounted in the lever and having a non-circular axial opening, the ends of the shaft sections being of similar non-circular formation, and adapted to engage the axial opening of the socket piece, and means for pivoting the lever for bodily swinging movement, and means carried by the shaft sections to normally center the lever with respect to the sections.

In testimony whereof I affix my signature. 50

THOMAS BEAVER.
